WIRE DRAWING APPARATUS

William H. MacDonald and Lawrence J. Woods,
Worcester, Mass.

Application December 15, 1943, Serial No. 514,382

1 Claim. (Cl. 205—13)

This invention relates to wire drawing apparatus, and more particularly to a machine having drawing drums arranged for drawing wire through a series of dies for reducing the size of the wire.

Standard wire drawing apparatus as heretofore used has comprised a series of dies of successively smaller gauge alternating with a set of drawing blocks or drums arranged to pull the wire through the dies. As the wire becomes reduced in diameter and consequently elongated, it must be moved at an increased speed by each successive block in such a series. This has been accomplished by the use of stepped drums of increasing size or by rotating each successive block in the series at a faster rate. Another construction has comprised two axially parallel drawing blocks or drums of the same diameter arranged with a set of dies therebetween to form a succession of wire drawing operations. The wire is pulled forward by a separate drawing block about which the wire is coiled. The block is conical in shape and the accumulating wire is forced laterally towards the reduced end of the block where it builds up as a loose coil. This coil is ultimately removed and inspected and then taken to a separate machine where it is wound on a spool for commercial purposes. This multiplicity of operations is expensive and time-wasting. Moreover, the number of drawing dies that could be used in such a machine for drawing the harder steels has been materially limited, and this has often required the use of two machines to obtain enough reduction in size.

The primary object of this invention is to overcome such problems and to provide a wire drawing machine which serves to draw the wire in a single and complete operation to its final size and to spool the wire directly for commercial purposes.

Another object is to provide a wire drawing and spooling machine wherein the spooling mechanism serves as a part of the wire drawing apparatus and holds the wire under a proper tension.

A further object of this invention is to provide a high speed machine which will draw either hard or soft steel wires and reduce the same to a final and finished condition and which winds the finished wire on a spool for commercial purposes, and whereby the wire drawing operation attains such perfection as not to require inspection and a subsequent separate spooling operation. Further objects will be apparent in the following disclosure.

Referring to the drawings which illustrate a preferred embodiment of this invention:

Fig. 1 is a top plan view of the machine, with parts omitted for the sake of clarity;

Fig. 2 is a diagrammatic showing of the arrangement of the wire drawing rolls, dies, spooling device;

Fig. 3 is a side elevation of the machine with parts broken away;

Fig. 4 is a vertical elevation on the line 4—4 of Fig. 3, which shows the wire spooling mechanism; and

Fig. 5 is a section on the line 5—5 of Fig. 1.

In our wire drawing machine, the wire is drawn through a multiplicity of dies 10 by means of a pair of wire drawing drums 11 and 12. The drums are cylindrical bodies of equal diameters and are driven at the same speeds. The wire 14 is drawn from a supply standard 15 suitably mounted for rotation at the side of the machine, and the wire passes around the rolls and through the dies in a desired arrangement, such as shown diagrammatically in Fig. 2. The bores of the die in the series are made progressively smaller so that the wire is gradually drawn to a smaller size and at the same time elongated. In the machine illustrated, no take-up is provided for the increasing length of wire, but the wire is coiled around the drawing drums one or more times after each pass through a die so that, because of the frictional gripping of the cylindrical drum on the wire coil, the drum serves as a capstan for pulling the wire through the adjacent die. That is, in the operation of a capstan, if a coil of wire or rope around the capstan is held tight, then it will be drawn forward at the speed of the capstan; but if the coil is loosened, then there is slippage and the capstan cannot move the wire. In our machine, each coil of wire around the drum serves to hold tight the coil of wire immediately behind it in the series and thus causes the latter to move the wire. The wire in the last coil in the series moves at the highest speed because of its maximum elongation, and the speed of all of the drums has to be sufficient to move that last coil at full speed. Hence, all other drums must slip through the wire, as well as draw it forward. Consequently, each portion of the drum, except at the last coil, slips within the coil and yet holds the coil with that degree of tightness which causes the preceding coil to do its work.

Heretofore, machines of this type have employed a special drawing block associated with a winding reel which receives a loose coil of wire from the last drawing drum in the series. That coiled wire must be removed periodically and

thereafter spooled on a separate machine after a required inspection or other necessary operations.

The primary feature of this invention involves using a wire spooling device as the ultimate or final capstan which holds the wire taut for the drawing blocks and determines the speed of the wire through the dies. That is, the spooling device which automatically winds the finished wire serves as the capstan which holds under tension the coil of wire on the adjacent drawing drum, so that each coil on the drums holds the wire tight in the preceding coil. Because of this arrangement, the wire drawing operation is so accurate that either a soft or a hard wire may be drawn to its final size and spooled automatically in the same operation and thus placed in condition for the commercial market.

The drawings show a preferred embodiment of this invention. Referring first to the wire drawing mechanism, the two cylindrical drums 11 and 12 of equal diameters are mounted on drive shafts 16 and 17 suitably supported in bearings on the walls of a tank 18. The dies 10 are usually individual disk shape bodies having a center portion of a hard material provided with a perforation of the required size. The dies are removably held against a set of upwardly projecting fingers or lugs on a cross piece 19 suitably mounted within the tank. The drums may revolve within a soap solution in the tank which aids in the wire drawing operation. The shafts 16 and 17 project beyond the right hand tank wall (Fig. 1) and are driven by sprockets 20 and 21 of the same size connected by a chain 22 which insures that the drums rotate at the same peripheral speed. A pulley 24 fixed on the shaft 17 is suitably driven by a belt, and an idler pulley 25 and a belt shifting device 26 may be employed to start and stop the drawing drums when desired.

A capstan or drum 30 is suitably mounted outside of the tank 18, and it has a guiding flange 31 located just below the horizontal line of travel of the wire 14 from the top of the drum 12. This capstan 30 may have one or more coils of the wire passed around it, so that it may serve to hold the wire tight in the last coil around the drawing drum 12 and thus cause the drum 12 to function as a drawing block. The capstan 30 is preferably mounted on a vertical shaft 33 carried in suitable bearings 34 on the machine frame, and the lower end of this shaft carries a pulley 35 which is driven by a belt 36 that passes over idlers 37 and a driving pulley 38 fixed on the shaft 16. The capstan 30 has an effective circumference equal to that of each of the drums 11 and 12, and the three are driven at the same peripheral rate. The wire 14 may be passed through suitable wire straightening rolls 39 and then coiled around the capstan 30, say, three times, after which it passes to the spooling mechanism, as shown in Fig. 2.

The wire does not slip on the capstan 30, and the latter therefore holds the wire under tension for the drawing operation. It is, however, required that the loops of wire around the capstan or block 30 be in turn held tight so that this capstan will function to provide the necessary tension for the next adjacent coil on the drum 12. In accordance with this invention, we provide that tension by passing the wire directly to a final spooling device which is so constructed and arranged that this spool holds the wire tight throughout the series of loops on the drums. The spool 40 is driven at the maximum rate required

to take up all of the elongated wire as it is delivered by the last loop on the drawing drum 12 and at the same time spool the wire in coils of increasing diameter.

After the wire passes the straighteners 39 and the capstan 30, it goes around an idler pulley 41 mounted to rotate on a vertical axis and thence around an idler 42 which leads the wire to an idler pulley 43 slidably mounted on the machine framework 44. This pulley 43 is loosely mounted on a long shaft 45 suitably supported on the frame and may move axially as the wire is spooled. The wire then passes to a reciprocating thread guiding pulley 46 which lays the wire on the spool in a tightly coiled arrangement or a close packing.

To effect the required reciprocation of the thread guide pulley 46, the guide (Fig. 4) is rotatably mounted on a short shaft carried by the arms of a yoke 48. This yoke is in turn removably secured by a screw 49 between the yoke arms 50 of a vertical member 51 which is fixed by screws to a slide bar 52. This slide bar reciprocates horizontally through suitable slide bearings or openings in the standards 44 of the machine.

Reciprocation of the slide bar 52 and the guide pulley 46 is effected by means of a heart-shaped cam 60 rotatably mounted on a shaft 61 carried by suitable bearings supported by depending brackets 62 on the framework. The shaft 61 carries a worm gear 63 which meshes with a horizontal worm 64 on a shaft carried by the frame 44. The worm is driven by a pulley 65 connected by a clutch 66 to the worm shaft. The pulley is in turn driven by a belt 67 receiving power from a pulley on the end of the shaft 17.

The cam roller 70 which rides on the face of the heart-shaped cam 60 is suitably mounted on the end of a rocking bell crank lever 71 pivoted at 72 on the base of the machine. A spring 73 holds the cam follower against the cam. The vertical arm 74 of the lever 71 has a slot 75 within which is adjustably positioned a pivot pin 76 carrying one end of a link 77. The link has a pivot pin 78 at its opposite end fitted in one of the holes 79 in the downwardly projecting end of the vertical bar 51 which is fixed on and reciprocates with the slide bar 52. The adjustment of the position of the link serves for different lengths of spools. Thus, as the cam 60 revolves, it causes the rocking lever 71 to move the slide bar 52 and the guide pulley 46 back and forth at a rate determined by the shape of the cam; and that rate is substantially uniform so that the wire will be coiled on the spool in a close packing.

In accordance with this invention, the spool 40 is driven at a rate which not only insures winding the elongated wire as fast as it is delivered by the drawing drums but also holds that wire tight on the capstan 30, which in turn holds the wire tight for the drawing drums. It is not sufficient merely to wind up the wire as it is received; nor is the wire allowed to build up a loose coil as has been the practice heretofore. It is essential that the wire be held and wound under a longitudinal tension which keeps it tight on all of the drums in the series.

This double function of spooling the wire and of holding the wire taut is accomplished by means of a spool driven by a friction clutch. The clutch drive illustrated in Figs. 1 and 5 comprises a pulley 80 driven by a belt 81 and a second pulley 82 on the end of the worm shaft 64. The pulley sizes are such that the empty spool 40 will be revolved fast enough to hold the wire tight when

it first starts the winding operation, and the clutch will slip increasingly as the wire coil builds up. The pulley 80 is loosely mounted on a shaft 83 which is keyed to a clutch plate 84 having a friction surface portion 85 frictionally engaging the side of the pulley 80. A spring 86, held in place by a collar 87 adjustably threaded on the shaft 83, presses against the driving clutch plate 84 and holds the parts in frictional engagement. The shaft 83 is suitably mounted in a bearing 88 formed as a part of the framework of the machine. The shaft 83 has a head 89 thereon which serves as a driving plate for rotating the spool 40.

The spool is adjustably mounted in axial alignment with the shaft 83, and in order that different sizes of spools may be filled with wire we have provided a construction wherein a spool 40 of a given size may be removably mounted on a supporting shaft 90 which slidably fits within the central hollow sleeve portion 91 of the spool. The shaft member 90 has a head 92 thereon and a projecting center 93 which fits within a central recess in the plate 89 and thus aligns the spool with the driving shaft 83. The plate 92 carries a pin 94 projecting on both sides into slots in the plate 89 and the spool. This pin serves to lock the parts together so that the driving plate 89 will drive the shaft 90 and the spool mounted thereon. A collar 95 of suitable size is held against the right hand end of the spool by means of a nut 96 threaded onto the shaft 90, which thus holds the left hand end of the spool in driving engagement with the driving plate 92. The right hand end of the shaft 90 is removably insertable into the upper open end of a U shaped slot formed as a bearing member 97 in the portion 98 of the framework. An L shaped screw 99 having a set nut thereon is threaded into the framework 98 and engages the right hand end of the shaft 90 and thus serves to force the driving head 92 into engagement with the driving head 89 of the friction driven shaft 83.

Thus supply spools 40 may be mounted on shaft members 90 away from the machine while the wire drawing proceeds. When a new spool is to be put into place, the machine is stopped and the old spool is removed by loosening the L shaped screw 99 and lifting the right hand end of the shaft 90 from its bearing slot and thus releasing the opposite end from driving connection with plate 89. Then the right hand end of a new shaft 90 is dropped into the slot of the open bearing 97 and the plate 92 is rotated to bring the pin 94 into a driving position. The screw 99 is then tightened slightly so as to force the parts in driving engagement. If a different length of spool 40 is to be used, then the collar 95 and locking nut 96 are adjusted accordingly, and at the same time the position of the link 17 (Fig. 4) is adjusted to give the correct throw or reciprocation to the bar 52 and the guide pulley 46 so as to wind the wire along the entire length of the spool in a close packing.

The operation of the wire drawing apparatus has been made clear in view of the above disclosure. The operator strings up his machine according to the nature and size of the wire being treated. For example, a 16 gauge steel wire up to 0.70 carbon may be reduced in size to a 35 gauge in a single stage by using from 15 to 20 dies in the machine, and the drawing may be accomplished at a rate as high as 1000 feet per minute. The harder the steel, the more turns will be made in each coil on the drawing drums to secure the desired traction. The number of dies is limited

by the size of the machine. We may use as many as 34 in a single wire drawing operation. In stringing up the machine, the operator passes the free end of the wire on the supply reel 15 first through a die and then around the drum 12 as a coil formed of one or several turns of wire. Thence, the wire passes freely to and around the drum 11, and again it is threaded through the next die 16 and again looped around the drum 12 one or more times and so on, until it has been passed through all of the dies to the last coil shown at the left hand end of Fig. 2 of the drawings. From this last coil on the cylindrical surface of the drum 12, the wire passes through the straightener 39 and around the capstan at least once, such as in three loops of wire. Thereafter, the wire passes over the various guiding pulleys to the winding spool 40. The leading end of the wire is suitably secured to the spool, or the operation may be started by the operator winding the wire on the rotating spool and catching it in place so as to provide sufficient frictional gripage. The spool holds the wire tight for the capstan 30 and the latter tightens the last coil on drum 12; and each loop of wire on the drums serves as a capstan held tight by the next following loop of wire. Thus this succession of capstans or drawing blocks serves to pull the wire through all of the dies. No wire will be drawn until the spool is able to tighten up on the wire coming from the capstan 30. The use of the intermediate capstan 30 makes it unnecessary for the spool to exert any more tensional force than that merely required to keep the wire tight on the capstan. The spool does not have to draw the wire. In the above description, the term coil has been used to designate one or more turns of wire around the drum or capstan. It will also be understood that the wire is wound on the spool in a close packing as distinguished from the loose formation of the wire coil heretofore formed by lateral movement of the wire from a conical drawing drum.

It will be appreciated that many modifications may be made in this construction and that various mechanical equivalents may be substituted for the constructions above described and illustrated in the drawings. Various types of wire drawing apparatus may be employed, whether or not they involve take-ups for the elongating wire; but it is an essential part of this invention that the wire be held taut by means of the ultimate spooling operation and that this tautness created by the spooling step will hold the wire taut on the various drawing blocks or drums which draw the wire, so that each part of the mechanism will operate while the wire is held taut by that spooling device and will stop operating as soon as the wire is loosened at the spooling end.

Hence the above disclosure is to be interpreted as illustrating the principles of this invention and a preferred embodiment and not as imposing limitations on the claim appended hereto.

We claim:

A wire drawing apparatus comprising two cylindrical drawing blocks of equal diameter arranged with their axes parallel and in a horizontal plane and a set of wire drawing dies therebetween having the wire strung alternately through each die and in a coil around a block, a tank within which said block and dies are mounted, a capstan outside of the tank and receiving the wire from the drums, power mechanism for rotating the blocks and capstan at the same peripheral rate, a framework outside of the tank, 75 bearings on the framework, a horizontal two-part

shaft supported by the bearings, a winding spool receiving the wire from said capstan which is removably mounted between said bearings on one part of the shaft, means including a spring pressed friction drive plate driven by said mechanism and arranged concentric with the other part of the shaft for rotating the same, a breakable driving connection between the spool and the driven part of the shaft, said spool and associated

parts being so constructed that the spool may be replaced without disturbing the friction drive, and means including a reciprocable guide, a driven cam and a variable throw connection between the cam and guide for laying wire on different lengths of spool.

WILLIAM H. MACDONALD.
LAWRENCE J. WOODS.
